UNITED STATES PATENT OFFICE

2,462,064

PRESSURE VESSEL FOR STORAGE OF LIQUIDS AT ABNORMALLY HIGH OR LOW TEMPERATURES

Harry C. Boardman, Chicago, Ill., assignor to Chicago Bridge & Iron Company, a corporation of Illinois

Application October 9, 1944, Serial No. 557,842

8 Claims. (Cl. 220—15)

1

This invention relates to a pressure vessel for the storage of liquids at abnormally high or low temperatures.

The present invention is particularly adapted for the storage of liquids at low temperatures and high pressures. It may also be used for the storage of hot liquids at high pressure. The ordinary carbon steel loses a great deal of its impact strength at very low or very high temperatures. For example, at temperatures suitable for the storage of liquefied hydrocarbons it is desirable to employ Monel metal or other high nickel alloys. In accordance with the present invention, a relatively thin inner shell member of temperature-resistant metal, such as Monel metal may be employed in the form of a fluid-tight shell of intersecting spherical segments. The outward stresses of these segments are transmitted along the lines of intersection to insulating supports of non-metallic material such as Marinite to an outer shell which is preferably fluid-tight and is preferably in the form of a regular polyhedron. This outer shell may be made of common carbon steel.

The invention is illustrated in the drawings, in which Fig. 1 is a plan view of one form of the improved tank; Fig. 2 is a vertical section taken along the line 2—2 in Fig. 1; Fig. 3 is a section taken along the line 3—3 in Fig. 1; Fig. 4 is a perspective view of the outside of the inner shell; Fig. 5 is a plan view of a modified form of the invention; and Fig. 6 is a section taken along the line 6—6 in Fig. 5.

In the form of the invention shown in Figs. 1 to 4, the spherical segments 10 intersect along the lines 11 which all fall in the planes of the diagonals of the cubical outer shell 12. The radially outward components of the stresses of the spherical segments are carried by non-metallic insulating supporting members 13 which extend to the edges of the cube 12. The cube 12 is made up of welded plates of ordinary carbon steel. The space 14 between the inner and outer shells is preferably evacuated in any suitable manner. Liquid may be introduced to and withdrawn from the inner shell in the usual manner by any pipe (not shown). The foundations for the vessel are not part of the present invention and accordingly are not shown. It will be observed that the apex 15 of each circular segment lies on the perpendicular from the center of the adjoining side 16 of the cube, and that planes connecting the adjacent corners of the intersections would form an inscribed cube.

In the form shown in Figures 5 and 6, the ex-

2

terior shell 12a is dodecahedral in shape, and the intersecting spherical segments 10a are twelve in number, the center of each segment again, however, being located on a perpendicular beneath the center of each side. The spherical segments are supported along the lines of intersection 11a by the Marinite supports 13a which extend in each case to, and only to, an edge of the outer dodecahedral shell.

10 The thin inner shell is free to expand and contract between the points of support, changing its radius of curvature as it does so.

The spherical segments need not have the same radius of curvature or the same thickness. Differences in the stresses which must be carried by the various segments may be adjusted by varying the thickness and holding the radius of curvature constant, or by varying the radius of curvature and having the thickness constant.

20 If it is desired not to use a vacuum, the space 14 may be left filled with air, or it may be filled up to the point of maximum expansion of the inner shell with a solid insulating medium. If the solid medium employed is compressible, as, for example, is the case with rock wool, the variations in the shape of the inner shell during expansion and contraction may be disregarded.

25 The foregoing detailed description has been given for clearness of understanding only, and no unnecessary limitations should be understood therefrom.

30 What I claim as new, and desire to secure by Letters Patent, is:

1. A pressure vessel for storing liquids at extremely high or low temperatures comprising an outer shell in the form of a polyhedron of carbon steel, diagonal insulating supports extending inwardly from the edges of said polyhedron to the intersections of spherical segments equal in number to the faces of the polyhedron and arranged symmetrically with respect to the sides thereof, the spherical segments being composed of a metal capable of retaining a substantial part of its strength at extreme temperatures, and forming a fluid-tight shell.

2. A vessel as set forth in claim 1, in which the polyhedron is a cube.

3. A vessel as set forth in claim 1, in which the polyhedron is a dodecahedron.

4. A pressure vessel for storing liquids at extremely high or low temperatures comprising: an outer shell in the form of a regular polyhedron; an inner shell made up of a plurality of spherical segments, said spherical segments being composed of a metal capable of retaining

a substantial part of its strength at extreme temperatures and said spherical segments intersecting in lines lying in the plane of the diagonals of said outer shell, and a plurality of insulating supports disposed only along said intersections, said insulating supports transmitting to the outer shell the outward components of the stresses of said segments.

5. A pressure vessel as set forth in claim 4 in which the inner and outer shells are gastight and the space intermediate said shells is evacuated.

6. A vessel as set forth in claim 4 in which the outer shell is a fluidtight carbon steel shell and in which the spherical segments are free to expand or contract between the supports by changing their radius of curvature.

7. A vessel as set forth in claim 4 in which the inner shell comprises six spherical segments and the outer shell is made up of six correspondingly disposed equal plane sides forming a cube.

8. A vessel as set forth in claim 4 in which the outer shell is in the form of a regular dodeca-

hedron and each face of the dodecahedron is subtended by one spherical segment.
